CLAIM

The ornamental design for a tape dispenser, as shown and described.

DESCRIPTION

FIG. 1 is a perspective front top view according to the present invention.

FIG. 2 is a perspective front top view in opened position according to the present invention.

FIG. 3 is a perspective left side view from above according to the present invention.

FIG. 4 is a perspective left side view from above in opened position according to the present invention.

FIG. 5 is a right side view according to the present invention.

FIG. 6 is a right side view in opened position according to the present invention.

FIG. 7 is a left side view according to the present invention.

FIG. 8 is a left side view in opened position according to the present invention.

FIG. 9 is a top view in opened position according to the present invention.

FIG. 10 is a top view according to the present invention.

FIG. 11 is a front view according to the present invention.

FIG. 12 is a front view in opened position according to the present invention.

FIG. 13 is a back view according to the present invention.

FIG. 14 is a back view in opened position according to the present invention.

FIG. 15 is a bottom view according to the present invention; and,

FIG. 16 is a bottom view in opened position according to the present invention.
